(57)

CLAIM

The ornamental design for a money clip, as shown and described.

DESCRIPTION

FIG. 1 is a front, first side, and bottom perspective view of a money clip embodying the new design;

FIG. 2 is a back, second side, and bottom perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

Any uniform repeating broken lines being presented depict portions of a money clip in which the claimed design is embodied and form no part of the claimed design.

1 Claim, 8 Drawing Sheets
